UNITED STATES PATENT OFFICE.

THOMAS M. DUDGEON, OF AVALON, PENNSYLVANIA.

FUEL BURNER AND MIXER.

SPECIFICATION forming part of Letters Patent No. 764,279, dated July 5, 1904.

Application filed October 17, 1903. Serial No. 177,476. (No model.)

To all whom it may concern:

Be it known that I, THOMAS M. DUDGEON, a citizen of the United States of America, residing at Avalon, in the county of Allegheny and State of Pennsylvania, have invented certain new and useful Improvements in Fuel Burners and Mixers, of which the following is a specification, reference being had therein to the accompanying drawings.

10 This invention relates to certain new and useful improvements in fuel burners and mixers, and relates more specifically to that class employed in connection with the burning of natural and artificial gas as a fuel.

15 One of the main objects of the invention is to construct a mixer of the burner of a single piece of sheet metal and provide the same with integral means for securing the same to the back of the burner. Means is provided 20 for forming an absolutely tight seal around the edge of the mixer, whereby none of the gas will be permitted to escape except through the port leading to the burner-front.

Another of the objects of the present invention is to so construct a burner as to feed 25 the gas thereto equally at all points and to provide means whereby the burner-front may not be damaged by undue pressure being brought to bear against the same.

30 It is a still further object of the invention to so construct the mixer of the burner as to offer no obstructions to the entrance of the fuel, and thereby avoid the common objection of the "back-flashing" of the fuel, due to the 35 uneven or rough surface within the mixer.

The invention further consists in the novel construction, combination, and arrangement of parts to be hereinafter more fully described, and specifically pointed out in the claims.

40 In describing the invention in detail reference is had to the accompanying drawings, forming a part of this specification, and wherein like numerals of reference indicate like parts throughout the several views, in which—

45 Figure 1 is a detail plan view of the blank from which the mixer is formed. Fig. 2 is a detail perspective view of the mixer detached from the burner-back. Fig. 3 is a transverse vertical sectional view of the burner complete. Fig. 4 is a front elevation of the same.

Fig. 5 is a detail plan view of a part of the burner-back, showing how the mixer is secured thereto. Fig. 6 is a detail plan view of a part of the burner-front.

Heretofore and before my invention it has 55 been the common practice to provide a cast-metal mixer, which is provided with apertured lugs adapted to be securely riveted to the burner-back. Many objections are to be found with this prior construction, as in event 60 of one of the lugs being broken when securing the mixer in position a tight joint between the mixer and burner-back cannot be obtained, and consequently the mixer is rendered useless, and in all probability the 65 burner-back will also be damaged to such an extent in the removing of the mixer that the same will be also rendered worthless. Furthermore, the mixer being made of cast metal is liable to be broken in shipment, so as to render 70 the burner worthless. In my invention I form the mixer of a single piece of bendable sheet metal, stamping out the blank by means of a suitable die and bending up this blank into the shape to form the mixer. The blank A, 75 as seen in Fig. 1 of the drawings, is produced, as stated, by means of a suitable die which cuts the same out to form the projecting lugs 1, the lugs 2, and lug 3 and an apertured lug 4. When the blank is so formed, I shape the same 80 by means of a press and fold over the wings 5 of the blank, overlapping the same, as seen in Fig. 2 of the drawings, and bending over the lug 3, as shown in said Fig. 2, to hold the wings in said overlapping engagement. I also shape 85 the blank by means of a press to produce the flange 6, as seen in Fig. 2, and bend up the lugs 1 at right angles to the flange and also bend up the apertured lug 4 at a right angle to the rear wall of the mixer. The sheet 7, 90 which forms the burner-back, is provided with slits made therein by the die or other suitable means to receive the lugs 1 of the burner, as clearly shown in Fig. 3 of the drawings. After these lugs have been inserted in the slits made in the burner-back they are clenched against the front of the burner-back by means of a suitable press. The lugs 1 are passed through the gasket or washer 8, on which the flange 6 rests, whereby to form a 95 100

perfectly tight seal to prevent the gas from escaping at any point except through opening 9, provided therefor in the burner-back. The apertured lug 4 is adapted to receive and 5 form a holder for the nipple or spud 10, to which the gas-inlet pipe 11 is connected, as seen in Fig. 3 of the drawings. The burner-back 7 is provided with vertical depressions 12 near one side edge of the burner-back, which 10 form passages or feedways to permit the gas to feed equally therethrough throughout the entire surface of the burner. The burner-front consists of a piece of sheet metal 14, corrugated to form the ridges 15, each of 15 which is provided with a row of openings 16, through which the gas is fed and at which point it will be ignited. The front of the burner is provided with a covering of asbestos, as shown at 17, as is the usual practice, 20 this asbestos, as in the ordinary manner, being placed so as not to cover up the rows of openings 16, as clearly illustrated in Fig. 4. The vertical ways or feed-passages 14 receive the fuel from the horizontally-extending channel 18, that communicates with openings 9, and feeds the said fuel to the remainder of the horizontal chambers 18 throughout the surface of the burner. The ridges 15, formed by the corrugating of the burner-front 14, 25 are extended only slightly beyond the vertical feed passages or ways 12—that is, are stopped intermediate the side edges of the said burner-front 14—and to take up the slack along the edges of the sheet which would be 30 caused by the corrugating of the said sheet to produce the ridges 15 I crimp or gather the edges of said sheet, as shown at 19. On these crimped or gathered edges 19 of the burner-front I place what is commonly known in the 35 trade as "heading," consisting of a plastic material, and then bend over the edges of the back onto the plastic material and crimped edges of the front plate and also onto the front plate at the upper and lower ends thereof. 40 To accomplish this, the back plate 8 is made of a size sufficiently large to permit the flanging or bending over of these edges onto the front plate. A gasket or washer of asbestos may be placed between the front plate 45 and the back plate at the upper and also at the lower end thereof.

In the employment of cast mixers it is practically impossible to make the same with a smooth interior surface, and the projections 50 or roughened portions thereof cause the back-flashing of the fuel, which tends to blacken the front of the burner, and thus destroy the appearance thereof. By forming the mixer of the single piece of sheet metal the interior surface 55 thereof with which the fuel comes in engagement is perfectly smooth and all danger of back-flashing is avoided. In the formation of the burner-front I employ a press to form the corrugations or ridges and also to produce the 60 openings 16 in such a manner as to leave no

projections on the inner face of the burner-front in the forming of the openings. Heretofore where these openings have been punched through the burner-front projections left on the back of the burner-front are liable to catch 70 and hold the carbon, which accumulates in such quantities as to clog up a number of the openings, and thus destroy the effectiveness of the burner. This is entirely obviated in the construction herein shown and described. In this 75 type of burners it is the common practice to provide a rear covering 21, of asbestos or other suitable material. The mixer being made of a single piece of sheet metal and formed entirely by dies and presswork is materially reduced in cost, as well as obtaining a construction by means of which the effectiveness of the burner is materially increased over the type 80 of burner having a cast-iron mixer secured thereto. 85

In connection with my improved burner I prefer to make the hood 22 detachable and adjustable. To accomplish this, the said hood is formed integral with a gutter 23 of substantially inverted-U shape which engages and 90 fits on the upper end of the burner. The hood being made of sheet metal covered with asbestos fiber may be readily bent to different inclines, so as to increase or decrease the opening leading to the chimney or flue, and thus 95 regulate the draft. For instance, in the case of a flue having a strong draft the hood may be bent down, so as to decrease the opening leading to the flue, and thus obtain a greater radiation of the heat thrown off by the burner, 100 while in the case of a flue having a weak draft the hood may be bent up, so as to increase the opening leading to the flue. This construction of hood is also advantageous, as in case of 105 accumulation of fumes in the room the hood may be bent upward to increase the opening to the flue and increase the draft, and after the fumes are drawn up the flue the hood may be again bent down to obtain the desired radiation. 110

While I have herein shown and described my invention as it is practiced by me, yet it will be obvious that various slight changes may be made in the details of construction without departing from the general spirit of 115 my invention.

Having fully described my invention, what I claim as new, and desire to secure by Letters Patent, is—

1. A burner comprising a burner-back having an opening, a burner-front having longitudinal corrugations and provided with crimped edges, said burner-back having its edges bent over upon the burner-front, substantially as 120 described.

2. In a burner, a mixer formed from a bendable blank having wings at one end which are bent upward and then inward to overlap each other, the remaining portion of the blank being approximately concavo-convex and pro- 125

130

vided at its upper edge with a flange, and a securing means carried by the flange.

3. A mixer formed from bendable sheet metal with a pair of wings at one end, said wings being bent upward and then inward where they are secured together, the remaining portion of said mixer having its upper wall open, in combination with a burner closing the open portion of the upper wall of said mixer, and a securing means.

4. In combination with a burner, a mixer formed from a blank of bendable material,

having integral bending securing-lugs adapted to project through the contiguous burner-wall and be bent thereon, and an integral apertured lug at the lower end of the burner extending at right angles to the body of the mixer.

In testimony whereof I affix my signature in the presence of two witnesses.

THOMAS M. DUDGEON.
